HYDRAULIC SYSTEM

Ralph E. Price, Highfield, Md., assignor to Landis
Tool Company, Waynesboro, Pa.

Application November 1, 1946, Serial No. 707,281

7 Claims. (Cl. 60—52)

1

This invention relates to hydraulic systems wherein use is made of very small volumes of fluid under pressure.

A limitation in any type of hydraulic pump is the ratio between volume of discharge and leakage. Where the capacity of the pump is large, the leakage is relatively small. In very small pumps the leakage may be equal to the discharge volume. Leakage is due to the fact that it is practically impossible to fit the running parts of a pump so that it will discharge a volume equal to its displacement. Clearances necessary to permit relative movement of parts also permit loss of fluid. A small amount of leakage occurs through relief valves and other types of valves. As mentioned above, this is more pronounced where the volume is small, since for a given system and pressure the leakage probably remains constant regardless of the volume passing through.

It is therefore an object of this invention to provide means for reducing leakage of fluid under pressure in a low capacity hydraulic system.

A further object is to provide two sources of fluid under pressure in which the pressure in one system regulates the pressure in the other system.

A further object is to provide a hydraulic system including differential pumps and means for reducing leakage in the differential output.

The drawing is a plan view of a grinding machine showing a grinding wheel feed mechanism which makes use of the hydraulic system which is the subject of this invention.

In the drawing, numeral 10 indicates the bed of a grinding machine, 11 a grinding wheel support slidably mounted thereon, and 12 a grinding wheel rotatably mounted on said support. A work carriage 13 is slidably mounted on bed 10 for movement in a direction transverse to that of the wheel support. Said work carriage has a headstock 14 and a footstock 15 mounted thereon for rotatably supporting a work piece to be operated on by said grinding wheel.

The means for effecting movement of wheel base 11 is described in detail in Patent No. 2,313,479, granted March 9, 1943.

This means consists of a piston 20 slidable in a cylinder 21 in bed 10. Said piston has a piston rod 23 in the form of a feed screw. The threads of said screw are in operative engagement with the teeth of a worm wheel 24. A positive stop 26 limits the endwise movement of feedscrew 23. Said worm wheel 24 is on the lower end of a vertical shaft 25 passing through the wheel base 11. Said shaft may be rotated by 55

means of a handwheel 27 to which it is connected by suitable gearing.

The means for effecting a grinding feed movement of wheel base 11 consists of a piston 30 slidably mounted in a cylinder 31 in bed 10. Said piston has a rod 32 on which rack teeth have been formed for engaging the teeth of gear 33 on piston rod 23 of piston 20. The length of stroke of piston 30 may be regulated by adjusting screw 34.

Fluid under pressure for actuating piston 20 in both directions and for resetting piston 30 is supplied by a pump 40 having an inlet 41 and a discharge line 42. A relief valve 43 is connected to said line 42. Line 42 leads to a reversing valve 44 from which fluid under pressure may be directed alternately through lines 45 and 46. Exhaust fluid from said lines is discharged through ports 47 and 48.

Fluid under pressure for moving piston 30 from right to left for the feeding movement is supplied by a pair of pumps 50 and 51 of the same displacement. However, pump 50 is operated at a slightly higher speed than pump 51 and therefore its output is proportionately higher. Pump 50 has an inlet 52 and a discharge line 53 leading to the right hand end of cylinder 31. Pump 51 is connected to line 53 and pumps from said line to the extents of its capacity. Pump 51

discharges through line 54, check valve 55 and line 56 to line 53. A by pass valve 57 is connected to line 54 so that the output of pump 51 may be returned to a reservoir (not shown). The function of check valve 55 is to prevent the output of pump 50 from flowing through lines 56, 54 and out through valve 57 when said valve is open.

There is no relief valve in this two pump system. The reason for this is because of the small volume of fluid passing through the system and the fact that conventional relief valves usually leak enough to interfere with the operation of such a low volume system.

Instead of using a conventional relief valve, a check valve 60 is inserted in line 61 connecting line 56 of the two pump system with line 46 of the rapid feed pressure system. This rapid feed system operates at a higher pressure than is required to move piston 30 and thus serves to hold valve 60 in closed position except when for any reason, the pressure in the two pump system becomes greater than that in the rapid feed system as when piston 30 stops at the end of its movement, in which case said valve will relieve the higher pressure into the rapid feed

system. During feeding operation the pressure in line 46 is sufficient to hold valve 60 closed.

When reversing valve 44 is in the position shown i. e. line 46 being connected to exhaust port 48, pressure is also reduced in line 53 through line 56, valve 60, line 61 and line 46. Exhaust fluid from cylinder 31 may then return through lines 53, 56, valve 60 and line 61 through line 46 and reversing valve 44 to exhaust line 48.

Operation

The feeding movement of grinding wheel 12 may be initiated by shifting valve 44 to the right against spring 62. In this position fluid under pressure from pump 40 will be directed through line 46 to cylinder 21 causing piston 20 to drive wheel base 11 to forward or operative position against stop 26. Pressure will be maintained in line 46 to hold screw 23 against said stop until the end of the grinding cycle when reversing valve 44 will be shifted to reset the feed mechanism. Also in this position switch 64 will be closed to initiate operation of timer 63 which will energize solenoid 65 to hold said switch closed. At the same time, pumps 50 and 51 supply fluid under pressure through lines 53, 54 and 56 to the right hand end of cylinder 31. Piston 30 and piston rod 32 rotate screw 23 so that at the end of the rapid feed movement of piston 20 determined by stop 26, the wheel support 11 will continue to move at a rate suitable for grinding due to the rotation of screw 23 in contact with worm wheel 24. Since said worm wheel cannot be rotated except by handwheel 27, it acts as a nut and moves along screw 23 carrying wheel base 11 with it.

After a predetermined amount of grinding which may be determined by either a sizing device or the timing mechanism 63, valve 57 actuated by said timer is opened and the output of pump 51 is returned to the reservoir (not shown). Since pump 51 is supplied by pump 50 which has a slightly higher output, the small volume which is the difference between the discharge volume of the two pumps continues to flow through line 53 to cylinder 31.

The movement of piston 30 and hence the rate of grinding feed is thus reduced in proportion to the reduction in volume of fluid supplied thereto. When this movement is timer controlled as it is in this case, piston 30 may reach the end of its stroke before the end of the timed period. The pressure in line 53, therefore, will build up to a point at which it equals or exceeds the pressure in line 46. At this point, check valve 60 becomes a relief valve and excess fluid is discharged into line 46.

When a work piece has been ground to size, valve 44 may be shifted either manually or automatically to the left hand position. In this case timer 63 breaks the circuit to solenoid 65 permitting spring 62 to shift valve 44 to the left and at the same time open switch 64. In this position of valve 44, line 46 will be opened to exhaust port 48. Fluid under pressure will be directed through line 45 to cylinders 21 and 31 to reset feed pistons 20 and 30 respectively. Exhaust fluid from cylinder 31 will pass through line 53 against pressure from pump 50 or both of the pumps 50 and 51 and through line 56 and valve 60 to line 46 which is connected to exhaust line 48 through reversing valve 44. In the absence of pressure in line 46 check valve 60 will open due to the pressure behind it and connect the two pump system including line 53 and cylinder 31 to exhaust.

Fluid under pressure from pump 40 will de 75

directed through line 45 which divides to supply fluid to the rod ends of both of the cylinders 21 and 31 thus retracting wheel 12 and resetting the grinding feed piston 30 against screw 34.

I claim:

1. A hydraulic system having a low volume section and a high volume section, said high volume section including a motor, a pump for supplying fluid under pressure thereto and a relief valve for relieving excess fluid, said low volume section including a motor and a source of fluid under pressure, a check valve between said low volume section and said high volume section, said check valve acting as a relief valve, the setting of which is dependent on the pressure in the high volume section and arranged to prevent a flow of fluid from said high volume section to said low volume section.

2. A hydraulic system having a low volume section and a high volume section, said high volume section including a motor, a pump for supplying fluid under pressure thereto and a relief valve for relieving excess fluid, said low volume section including a motor and a source of fluid under pressure, a connection between said high volume section and said low volume section, a check valve in said connection arranged to permit escape of excess fluid from said low volume section to said high volume section when the pressure in said low volume section is greater than the pressure in said high volume section.

3. A hydraulic system having a low volume section and a high volume section, said high volume section including a motor, a pump for supplying fluid under pressure thereto and a relief valve for relieving excess fluid, said low volume section including a motor and a source of fluid under pressure, a connection between said high volume section and said low volume section, a check valve in said connection arranged to permit relief into said high volume section of pressure in said low volume section in excess of the pressure in said high volume section.

4. A hydraulic system having a low volume section and a high volume section, said high volume section including a motor, a pump for supplying fluid under pressure thereto and a relief valve for relieving excess fluid, said low volume section including a motor and a source of fluid under pressure, a connection between said high volume section and said low volume section, a check valve in said connection, said check valve being held in closed position by the fluid in said high volume section, said fluid and said check valve combining to regulate the pressure in said low volume section.

5. In a hydraulic system, a hydraulic motor, a source of fluid under pressure for said motor comprising two pumps of slightly different capacities connected in series so that the smaller pump pumps from the larger pump to the motor to the limit of its capacity, a direct connection from the larger pump to said motor for conducting the small volume of fluid which is the difference in capacities of the two pumps, a by pass valve for diverting the output of the smaller pump, a check valve between the motor and said valve, a second hydraulic system operable at a higher pressure than said first system, a connection including a check valve between said first system and said second system whereby an excess of pressure in said first system will be released into said second system at a pressure determined by the pressure in said second system,

6. In a hydraulic system having a motor, a high volume and a low volume section, the method of preventing leakage in said low volume section which consists in connecting said sections, placing a check valve in said connection positioned to permit passage of fluid from said low volume section to said high volume section, using the high pressure in said high volume section to hold said valve closed during movement of said motor but permitting the relief of excess pressure in said low volume section into said high volume section when the pressure in said low volume section is greater than the pressure in said high volume section.

7. A hydraulic system having a low volume section and a high volume section, the high volume section including a motor, a pump for supplying the fluid under pressure thereto, and a relief valve for relieving excess fluid in said system, said low volume section including a motor

5

and to one side of said second motor, a check valve between said low volume section and said high volume section for discharging fluid from said low volume section into said high volume section when said low volume motor is moved in opposition to said low volume fluid supply.
